UNITED STATES PATENT OFFICE.

CHARLES E. FETHEROLE, OF COLUMBUS, OHIO, ASSIGNOR TO THE JEFFREY MANUFACTURING COMPANY, A CORPORATION OF OHIO.

WIRE-CUTTING MACHINE.

1,048,141.

Specification of Letters Patent.

Patented Dec. 24, 1912.

Application filed July 14, 1910. Serial No. 572,016.

To all whom it may concern:

Be it known that I, CHARLES E. FETHEROLE, a citizen of the United States, residing at Columbus, in the county of Franklin and State of Ohio, have invented certain new and useful Improvements in Wire-Cutting Machines, of which the following is a specification, reference being had therein to the accompanying drawing.

10 This invention relates to improvements in machines for straightening and cutting wire, and is especially adapted for use in connection with flat insulated wire such as is used for the armature windings of dynamos and motors. Machines embodying my invention are, however, equally well adapted for straightening and cutting other kinds of wire.

20 Among the objects of my invention are to provide improved means for feeding the wire, improved means for cutting it, improved means for regulating the length of the cut sections, and improved means for actuating and controlling the feeding and 25 cutting means.

Other objects will appear from the following specification.

In the accompanying drawings which form a part of this specification, I have 30 shown the embodiment of my invention which I at present prefer. It will be understood, however, that various changes in construction and in arrangement of parts may be made within the scope of my invention.

35 Of the drawings—Figure 1 is a side elevation. Fig. 2 is a plan view. Fig. 3 is a fragmentary view, partly in cross-section, showing the shearing mechanism and the 40 operating devices therefor. Fig. 4 is a view partly in cross section, taken along the line 4—4 of Fig. 2. Fig. 5 is a fragmentary cross-sectional view taken along the line 5—5 of Fig. 3. Fig. 6 is a detail plan view 45 of the main controlling switch. Fig. 7 is a side elevation of the controlling switch and the parts adjacent thereto. Fig. 8 is a cross sectional view taken along the line 8—8 of Fig. 6. Fig. 9 is a cross sectional view taken 50 along the line 9—9 of Fig. 6. Fig. 10 is a cross sectional view taken along the line 10—10 of Fig. 2. Fig. 11 is a diagrammatic view showing the electrical connections. Fig. 12 is a detailed view of the upper feed 55 roll shifting device.

Referring to the drawings, 1 represents the standard or table upon which the machine as a whole is mounted.

2 is the bed plate of the machine which is secured to the table 1, and which is provided with a long tubular extension 3. This extension 3 may be of any desired length, depending upon the maximum length of wire which it is desired to cut. The extension is mounted upon legs 4 which may be spaced at convenient intervals.

50 Adjacent the machine is a standard 5 having a spindle 6 upon which may be mounted a spool 7 having wire wound upon it.

55 Mounted upon the bed plate 2 of the machine is a wire straightener, indicated as a whole by 9. This comprises a suitable support 9 upon which there is mounted a plurality of horizontal rollers 10 which, on account of their relative arrangement, are 70 adapted to straighten the wire in a horizontal plane. In advance of the rollers 10 are two vertical rollers 12 mounted on stationary spindles and a third vertical roller 13 mounted upon a spindle which is vertically adjustable by means of a screw 14. By means of this screw 14 the straightener 75 may be adjusted in accordance with the stiffness or curvature of the wire upon which it is operating.

80 18 is a shaft rotatably mounted in the pedestals 15 and 16 and the bearing bracket 17.

85 19 is a driving pulley freely mounted on the shaft 18. Connected with the pulley 19 and adapted to rotate with it is a spur gear 20 and the driving element 21 of an electromagnetic clutch which will be more fully described hereafter.

90 22 represents the driven element of the clutch and is keyed to the shaft 18.

95 Parallel to and directly above the shaft 18 is a rotatable shaft 23 mounted at one end in a bearing 16^a which is pivotally mounted on the pedestal 16, and at the other end in a bearing 15^a which is slidably mounted in the pedestal 15. The shaft 23 is driven from the shaft 18 by means of a pair of spur gears 24. Feed rollers 25 and 26 are secured to the ends of the shafts 18 and 23 and are adapted to engage with the upper and lower sides of the wire which is designated in the drawings by 8. The feed rollers 25 and 26 are in line with the straightening rollers and with the spool 7 and are adapted to grip the wire 100 to draw it from the spool between the 105 8 to draw it from the spool between the 110

straightening rollers. The outer end of the shaft 23 is vertically movable. The screw 31, acting through the spring 31^a serves to maintain a pressure on the bearing 15^a, and to this force the roller 26 against the upper surface of the wire. A lever 15^b is provided for lifting the roller 26 in order to facilitate the threading of wire through the machine when a new spool of wire is put in place. The wire passes from the feed rollers through the tubular guide 27 between the jaws 28 and 29 of the shearing device and into the guide-way 30 of the measuring device 30^a.

Referring now more particularly to Figs. 3 and 4 of the drawings, it will be noted that the stationary jaw 28 of the shearing device is formed as a part of the casting 28^a which is attached to the bed plate 2. The movable jaw 29 of the shearing device is formed on a member 29^a which is mounted on a pivot 33 journaled in a bearing in the casting 28^a and held in place by lock nuts 34. At the rear part of the member 29^a there is formed an arm 35 which carries a roller 36 mounted on an axis at right angles to the pivot 33.

40 is a shaft parallel to the shaft 18 and rotatably mounted in bearings 41 and 42 which are secured to the bed plate 2. The shaft 40 is driven from the pulley 19 by means of the gear wheel 44 which meshes with the gear wheel 20 and by means of a magnetic clutch, one member of which, 43, is attached to the gear wheel 44, and the other member of which, 39, is attached to the shaft. This clutch will be hereinafter described in detail.

Secured to the shaft 40 is a cam 38 which is adapted to engage the pulley 36 on the arm 35. The pulley is maintained in engagement with the cam by means of the spring 37 which acts through the rod 37^a. The tension of the spring may be adjusted by means of the nut 37^b on the rod 37^a. It will be noted that the cam 38 is frusto-conoidal in shape so that there will be full engagement with the roller for all positions. The shear member 29 is provided with a downward extending arm 45 which is provided with a laterally extending pin 46.

48 is a lever pivoted to the bed plate 2 at 49, and provided with a longitudinal slot 47 through which the pin 46 passes.

54 is a shaft rotatably mounted in suitable bearings on the brackets 56 which are mounted on the tubular extension 3 of the bed plate 2. The shaft 54 is connected at its rear end with the upper end of the lever 48 by means of an arm 58 and a link 51, the link being connected with the arm and with the lever 48 at 52 and 50 respectively. It will be noted that by means of the system of levers and links which has been described, the shaft 54 will be rocked back and forth

through a small angle at each actuation of the shear.

The measuring device comprises a guide-way 30 which consists of a stationary bar 55 having in its bottom a groove 55^a. The bar 55 is supported on the brackets 56. A bar 58 serves as a floor for the groove or trough 55^a and is mounted by means of brackets 59 on the shaft 54. The wire to be cut is fed by the rollers 25 and 26 into the groove 55^a. The connections between the shearing device and the shaft 54 are such that as the shear is moved the floor 58 drops and permits the severed section of wire to fall into racks 57 which are secured to the brackets 56.

61 is an endless steel tape or belt which passes over the rollers 62 and 63 which are mounted at the ends of the bar 55. The trough 55^a is provided at its upper part with two opposite laterally extending grooves 60 which are adapted to receive the lower strand of the tape 61. Permanently secured to the tape 61 is a depending lug or stop 64 which is adapted to entirely close the passageway through the trough 55^a. This stop is most clearly shown in Fig. 7. At a convenient point along the bar 55 there is provided an electric controller switch which is mounted upon a plate 67. The plate 67 is provided with a depending bearing boss 66 in which there is rotatably mounted a vertical shaft 68, upon the lower end of which there is a bevel pinion 69 adapted to mesh with a bevel gear 70 on the shaft 54. Secured to the upper end of the shaft 68 is a head 71 having a finger 72.

74 is a switch blade rotatably mounted on the shaft 68 between the head 71 and the plate 67. At one side the blade 74 is provided with a notch 77 adapted to be engaged by a pivotally mounted latch 78. A spring 79 tends to hold the latch in engagement with the notch.

65 is a clamp adapted to be secured to the upper strand of the tape 61 at any desired point. The plate 67 is provided with a guide-way 82 for the clamp. This guide-way is provided with a slot through which extends a depending pin 82 which is adapted to engage the latch 78 to release it from the notch 77. A spring 76 attached at one end to the pin 75 on the plate 67 and at the other end to the upper part of the pin 73 is secured to the switch blade 74. When the latch 78 releases the switch blade the spring 76 immediately moves it into the position shown by dotted lines in Fig. 6.

84 is an insulated plate mounted upon the switch blade 74 and carries a contact plate 83.

87 and 90 are stationary insulating blocks secured to the plate 67. The block 90 is provided with fingers 88 and 89 adapted to engage the contact plate 83 when the switch

arm is in one position, and the block 87 is provided with contact fingers 85 and 86 adapted to engage the contact plate when the switch arm is in the other position.

5 The operation of the switch is as follows: When the end of the wire to be cut engages the stop 64 it moves the tape 61 and with it the pin 81 a sufficient distance to disengage the latch 78 from the notch 77. The spring 76 immediately throws the switch arm into the position shown by dotted lines in Fig. 6, the circuit being thus broken through the fingers 88 and 89 and established through the fingers 85 and 86. As soon as the wire 15 has been cut off it is dropped by the floor 58 and in this way the stop 64 is released. The spring 79 immediately tends to return the latch 78 and with it the tape 61 to their original positions. The same movement of 20 the shaft 54 which releases the wire from the trough also actuates the shaft 68 which, by means of the finger 72 and the pin 73, returns the switch arm 74 to its original position.

25 I have found from experience that occasionally the wire will foul and work its way out between the door 58 and the bottom of the bar 55. When this occurs, the wire, of course, fails to engage the stop 64 and the controlling switch is not operated. In order to prevent this difficulty I provide contacts 97 and 99 which are connected into the electrical circuit of the machine in a manner hereinafter to be set forth. The contact 99 is secured to the door 58, and the contact 97 is preferably in the form of a screw adjustable in the lug 98. The two contacts are so positioned relative to each other that when the door 58 is fully closed, 35 electric connection will be established through the contacts. When the door is partly open, as is the case when a wire is between it and the lower surface of the bar 55, electrical connection is broken.

40 45 I will now describe somewhat more in detail the electric clutches which have been heretofore mentioned. These clutches are similar in construction and it will therefore be necessary to describe but one of them.

50 Referring to Fig. 3, 43 is the driving element which is secured to the driving gear. The element 43 is provided with an annular groove in which there is a coil 105 which is connected, by means of wires passing 55 through the insulated bushings 106 and 107, with the insulated collector rings 108 and 109. The rings of the shear clutch are provided with contact brushes 113 and 114 and the rings of the feed roller clutch are provided with brushes 115 and 116. A diaphragm 112 is sprung into annular notches in the groove for the coil and serves to protect the coil against injury. A disk 112^a of non-magnetic material is preferably provided between the elements 39 and 43 to

prevent their sticking together through the influence of residual magnetism.

To insure the prompt stoppage of the driven elements of the clutches, each of them is provided with a friction brake which 70 consists of a brake-band 100 held in tension by a spring 101 which is mounted on a rod 103 and adjusted by means of a nut 102 on the rod. The tension on the brake-bands is very light and the brakes are kept in engagement at all times. In this way there is 75 a slight loss of power, but this is insignificant.

117 represents as a whole a switch-board which is mounted on the bed plate 2 by 80 means of suitable braces 118. The switch-board carries a number of incandescent lamps 119 which are connected in parallel and which are used as a rheostat to regulate the voltage of the current supplied to the machine. Two snap switches 120 are provided to control the circuits, and two carbon 85 resistance pencils 121 shunt the coils of the clutches to guard the insulation against puncture by the inductive kick.

Attached to the shear arm 35 is a clip 122 to which is connected a rod 123 which engages with an automatic counter 124. This counter may be of any desired construction, but I prefer to use a counter which is provided with means for interrupting the electric circuit after a certain predetermined number of actuations. In this way the machine may be adapted for the cutting of a definite number of wires and for automatically stopping after this definite number has 90 been cut.

I prefer to provide the shaft 23 with a pulley 125 over which passes a belt 126 which engages a suitable groove 127 formed 105 on the spool 7. In this way the spool 7 is positively moved and the tension on the wire 8 is reduced.

As shown in Figs. 3 and 5, I provide electrical contact devices on the shear arm 35. Mounted upon opposite sides of the shear 110 arm are two insulating blocks 91 and 92 carrying contact plates 93 and 94, respectively. A pair of contact fingers 95 are provided to engage with the contact plate 93 when the shear arm is in its lower position. A pair of contact fingers 96 are provided to engage with the contact plate 94 when the shear arm is in its raised position.

The electrical connections will be understood from a study of Fig. 11. Current is led to the machine from the elements 119 and passes through one of the switches 120 to one of the contact fingers 95. Supposing the shear to be in its normal position, the 125 arm 35 will be depressed and contact will be established by the plate 93 between the two fingers 95. Supposing the controlling switch to be in its normal position, contact will be established between the fingers 88 and 89 130.

by the plate 83. Supposing the door 58 to be in its closed position, connection will be established between the contacts 99 and 97.

128 designates the circuit breaking device 5 connected with the counter, and for present purposes this can be considered as closed. The current then passes through the circuit which has been described to the clutch 21 which serves to rotate the shaft 18 and the 10 feed rollers 25 and 26. The feed rollers continue to operate until the end of the wire engages the stop 64, whereupon the controlling switch is actuated and the circuit is broken between the fingers 88 and 89 and 15 established between the fingers 85 and 86. The clutch 21 is thus deenergized and the feed rollers stop. The clutch 43 is energized and the shear is actuated. The operation of the controlling switch is quite rapid and in 20 order to prevent the transfer of current from the clutch 43 to the clutch 21 before the shearing operation is complete, I provide the additional contacts 95 and 96. As soon as the movement of the shear is started, the circuit is broken between the contacts 95, and 25 established between the contacts 96. In this way the current to the clutch 43 is maintained until the completion of the shearing operation, regardless of the action of the 30 controlling switch, and in the same way the current is cut off from the clutch 21 until the shear has reached its inoperative position. When the proper number of wires have been cut, the counting device breaks 35 the circuit at 128 and the operation of the feed rollers is stopped.

What I claim is:

1. In a wire cutting machine, the combination of a wire feeding mechanism, a wire 40 cutting mechanism, frictional braking devices on said mechanisms, and means in advance of the feeding mechanism and cutting mechanism for controlling the said mechanisms, said means being adapted to be operated by the forward end of the wire, substantially as set forth.

2. In a wire cutting machine, the combination with a feeding and cutting mechanism, of an endless belt adapted to operate the 50 said feeding and cutting mechanism, and an adjustable belt actuating stop adapted to be operated by the forward end of the wire.

3. In a wire cutting machine, the combination with a feeding and cutting mechanism, of a controlling device comprising an endless belt, one strand of which is adjacent the path of the wire, a stop on the belt adapted to be engaged by the forward end of the wire to move the belt, and means 60 whereby the movement of the belt controls the operation of the cutting mechanism.

4. In a wire cutting machine, the combination with a feeding and cutting mechanism, of a controlling device comprising a wire 65 receiving trough, an endless belt, one strand

of which is adjacent the trough, a stop on the belt and within the trough adapted to be engaged by the forward end of the wire to move the belt, and means whereby the movement of the belt controls the operation 70 of the feeding and cutting mechanism, substantially as set forth.

5. In a wire cutting machine, the combination with a feeding and cutting mechanism, of a device comprising a wire receiving trough, an endless belt adjacent the trough, a stop secured to the belt and lying within the trough, the said stop being adapted to be engaged by the end of the wire to move the belt, a means for controlling the 75 operation of the feeding and cutting mechanism, and means for connecting the said controlling mechanism with the belt at any desired point, substantially as set forth.

6. In a machine for cutting wire, the combination with a feeding and cutting mechanism, of a device comprising a wire receiving trough, an endless belt, one strand of which lies at one side of the trough, a stop movable within the trough and secured to 80 the said strand of the belt, the said stop being adapted to be engaged by the end of the wire, and a controlling means for the cutting and feeding mechanism adapted to be connected to the other strand of the belt 85 at any desired point to adjust the operation 90 of the machine for cutting wires of any desired length, substantially as set forth.

7. In a wire cutting machine, the combination of a feeding mechanism, a cutting mechanism, electrically controlled operating means for the said mechanisms, an electric switch adapted to control the supply of current to the said operating means, and means whereby the switch may be operated by the 100 movement of the wire to be cut, substantially 105 as set forth.

8. In a wire cutting machine, the combination of a wire feeding mechanism, an electrically controlled device for operating the said feeding mechanism, a wire cutting mechanism, an electrically controlled device for operating the said cutting mechanism, an electric switch adapted for alternately supplying current to the said operating devices, and means whereby the switch may be controlled by the movement of the end of the wire to be cut, substantially as set forth.

9. In a wire cutting machine, the combination with feeding and cutting mechanisms, of a wire receiving trough having a continuous hinged bottom, and means for moving the said bottom to release the wire when it has been severed by the cutting mechanism, substantially as set forth.

10. In a wire cutting machine, the combination of a wire feeding mechanism, a wire cutting mechanism, a tubular wire receiving trough having one continuous hinged side, means within the trough adapted for 125 130

- engagement by the end of the wire to control the said cutting and feeding mechanisms, and means for moving the said hinged side to release the wire after it has been severed by the cutting mechanism, substantially as set forth. 70
11. In a wire cutting machine, the combination of a feeding mechanism, a cutting mechanism, a wire receiving trough having a continuous hinged side, and means adapted to be controlled by engagement with the end of the wire for moving the said hinged side to release the wire from the trough, substantially as set forth. 75
12. In a wire cutting machine, the combination of a feeding mechanism, a cutting mechanism, a wire receiving trough having a movable side, means for moving the said side to release the wire when it has been severed by the cutting mechanism, and means connected with the said movable side for stopping the operation of the machine when the said side does not return to normal position after movement, substantially as set forth. 80
13. In a wire cutting machine, the combination of a feeding mechanism, a cutting mechanism, electrical devices for controlling the said mechanisms, a wire receiving trough having a movable side, means for moving the said side to release the wire after it has been severed by the cutting mechanism, two electrical contacts located respectively on the said trough and on the said movable trough side, the said contacts being in engagement only when the said side is in normal closed position, and electrical connections whereby the current for controlling the operating device for the feeding mechanism passes through the said contacts, substantially as set forth. 85
14. In a wire cutting machine, the combination with a feeding and cutting mechanism, of a device comprising an endless belt adjacent the path of the wire, a stop secured to the belt, the said stop being adapted to be engaged by the end of the wire to move the belt, means for controlling the operation of the feeding and cutting mechanism, and connecting means between said controlling mechanism and the belt at any desired point. 90
15. In a wire cutting machine, the combination of a feeding mechanism, an operating device therefor, a cutting mechanism, an operating device therefor, means controlled by the end of the wire for stopping the action of the feeding mechanism and simultaneously starting the action of the cutting mechanism, and means for automatically starting the feeding mechanism after the completion of the operation of the cutting mechanism, substantially as set forth. 95
16. In a wire cutting machine, the combination of a feeding mechanism, an electrically controlled operating device therefor, a cutting mechanism, an electrically controlled operating device therefor, an electric switch normally directing current through the operating device for the feeding mechanism and adapted to be operated by the end of the wire after it has moved a predetermined distance beyond the cutting mechanism, the said switch being adapted to deenergize the controlling device for the feeding mechanism and to simultaneously energize the controlling device for the cutting mechanism, means for automatically returning the said switch to normal position, and a supplemental switch device adapted to interrupt the connection to the feeding mechanism controlling device and to maintain the connection to the cutting mechanism controlling device until the completion of the operation of the cutting mechanism, substantially as set forth. 100
17. In a machine for cutting wire, the combination of a feeding mechanism, an electrically controlled operating device therefor, a cutting mechanism, an electrically controlled operating device therefor, an electric switch normally directing current through the operating device for the feeding mechanism and adapted to be operated by the end of the wire after it is moved a predetermined distance beyond the cutting mechanism, the said switch being adapted to deenergize the controlling device for the feeding mechanism and to simultaneously energize the controlling device for the cutting mechanism, and means operatively connected with the cutting mechanism and with the switch for returning the switch to normal position as the cutting mechanism operates, substantially as set forth. 105
18. In a wire cutting machine, the combination of a feeding mechanism, a cutting mechanism, a movable receiving device for the wire, controlling means adapted to be operatively engaged by the end of the wire for stopping the action of the feeding mechanism and starting the action of the cutting mechanism, and means operatively connected with the cutting mechanism for moving the wire receiving device to release the wire and for operating the said controlling means to stop the action of the cutting mechanism and start the action of the feeding mechanism, substantially as set forth. 110
19. In a wire cutting machine, the combination with a feeding mechanism and a cutting mechanism, of a movable wire receiving device, a rock shaft parallel to and supporting the said receiving device, a controlling device adapted to be operatively engaged by the end of the wire to stop the action of the feeding mechanism and start the action of the cutting mechanism, operative connections between the rock shaft and the said controlling device, and operative connections between the cutting 115
- 60 65 70 75 80 85 90 95 100 105 110 115 120 125 130

mechanism and the shaft whereby the shaft is rocked by the movement of the cutting mechanism to release the wire from the wire receiving device and to operate the controlling device to stop the action of the cutting mechanism and start the action of the feeding mechanism, substantially as set forth.

20. In a wire cutting machine, the combination of a feeding mechanism, a cutting mechanism, a movable wire receiving device, a rock shaft parallel to the wire receiving device upon which the said device is mounted, connections between the said rock shaft and the cutting mechanism whereby the shaft is rocked upon the actuation of the cutting mechanism to release the wire from the receiving device, substantially as set forth.

21. In a wire cutting machine, the combination of two parallel shafts, a feeding mechanism operatively connected with one shaft, a cutting mechanism operatively connected with the other shaft, two magnetic clutches each having its driving element freely rotatable on one of the shafts, and each having its driven element secured to one of the shafts, operative connections between the two driving elements, means for actuating the said driving elements, and electrical switch devices for alternately energizing the said driving elements to alternately actuate the said feeding mechanism and the said cutting mechanism, substantially as set forth.

22. In a wire cutting machine, the combination of two rotatable shafts, a feeding mechanism operatively connected with one of them, a cutting mechanism operatively connected with the other of them, magnetic clutches, one on each of the shafts, each of the said clutches having a driving element rotatable on its shaft and a driven element secured to the shaft, means for continuously actuating the said driving elements, automatically controlled electric switch devices for energizing and deenergizing the said clutches, and a brake device engaging each driven clutch element to check its movement when the clutch is deenergized, substantially as set forth.

23. In a wire cutting machine, the combination with a feeding device and a cutting device, of a spool adapted for holding a coil of wire, and means independent of the wire to be cut for rotating the said spool when the feeding device is in operation, substantially as set forth.

24. In a wire cutting machine, the combination with a feeding device, of a cutting device comprising a stationary shear, a pivoted movable shear provided with an operating roller, a rotatably mounted cam adapted to operatively engage the said roller, a continuously rotating driving element, and means for intermittently connecting the said

rotating element with the said cam for rotating it, substantially as set forth.

25. In a wire cutting machine, the combination of a feeding device and a cutting device comprising a shear, a rotatable cam for operating the shear, and automatic means for intermittently rotating the cam through a definite angle, substantially as set forth.

26. In a machine for cutting wire, the combination with a feeding and cutting mechanism, of an endless belt, one strand of which lies along the path of the wire, a stop secured to the said strand of the belt, the said stop being adapted to be engaged by the end of the wire, and a controlling means for the cutting and feeding mechanism adapted to be connected to the other strand of the belt at any desired point to adjust the operation of the machine for cutting wires of any desired length, substantially as set forth.

27. In a wire cutting machine, the combination with a cutting device, of a feeding device comprising a pair of rollers adapted to frictionally engage the wire at opposite sides, means for adjustably and yieldingly holding one of the said rollers against the wire, and means for separating one of the said rollers from the other and for holding it in the said separated position, substantially as set forth.

28. In a wire cutting machine, the combination of a pair of parallel freely rotatable shafts, gearing between the said shafts, wire engaging rollers mounted upon the said shafts, a magnetic clutch mounted upon one of the said shafts and having its driven element secured thereto and its driving element rotatable thereon, means for continuously rotating the driving element, and automatic switch devices for intermittently actuating the clutch to rotate the said shafts and the said rollers, substantially as set forth.

29. In a wire cutting machine, the combination of a feeding mechanism, a cutting mechanism, electrically controlled operating means for said cutting mechanism, an electric switch adapted to control the supply of current to the said operating means, and means whereby the switch may be operated by the movement of the wire to be cut.

30. In a wire cutting machine, the combination of a feeding mechanism, a cutting mechanism, electrical devices for controlling the said mechanisms, a wire receiving trough having a movable side, means for moving the said side to release the wire after it has been severed by the cutting mechanism, two electrical contacts located respectively on the said movable trough side and a fixed portion of the machine, the said contacts being in engagement only when the said side is in normal closed position, and electrical connections whereby the current for controlling the operating devices for the feeding mecha-

nism passes through the said contacts, substantially as set forth.

31. In a wire cutting machine, the combination of a feeding mechanism, a cutting mechanism, an electrically controlled operating device for said cutting mechanism, an electric switch adapted to be operated by the end of the wire after it has moved a predetermined distance beyond the cutting mechanism, the said switch being adapted to energize the controlling device for the cutting mechanism, and means for automatically returning the said switch to normal position.
32. In a wire cutting machine, the combination of two parallel shafts, a feeding mechanism operatively connected with one shaft, a cutting mechanism operatively connected with the other shaft, a magnetic clutch having its driving element freely rotatable on the cutting mechanism shaft and a driven element secured on said shaft, operative connections for driving the two shafts, and an electrical switch device for energiz-

ing the said magnetic clutch, substantially as set forth.

33. In a wire cutting machine, the combination of two rotatable shafts, a feeding mechanism operatively connected with one of them, a cutting mechanism operatively connected with the other, two clutches, one on each of the shafts, each of said clutches having a driving element rotatable on its shaft and a driven element secured to the shaft, means for continuously actuating the said driving elements, automatically controlled devices for engaging and disengaging the said clutches, and a brake device engaging each driven clutch element to check its movement when the clutch is disengaged, substantially as set forth.

In testimony whereof I affix my signature, in presence of two witnesses.

CHARLES E. FETHEROLF.
